UNITED STATES PATENT OFFICE

148,549

DESIGN FOR A LAPEL PIN OR SIMILAR ARTICLE

Bernard Kohn, New York, N. Y.

Application May 3, 1946, Serial No. 129,263

Term of patent 3½ years

(Cl. D45—19)

To all whom it may concern:

Be it known that I, Bernard Kohn, a citizen of the United States, residing in New York city, county of Bronx, and State of New York, have invented a new, original, and ornamental Design for a Lapel Pin or Similar Article, of which the following is a specification, reference being had to the accompanying drawing, forming part thereof.

In the drawing:

I claim:

The ornamental design for a lapel pin or similar article, as shown.

BERNARD KOHN.
